UNITED STATES PATENT OFFICE.

FRANK W. BROWN, OF FORT DODGE, IOWA.

SNOWPLOW.

Application filed August 7, 1924. Serial No. 730,692.

To all whom it may concern:

Be it known that I, FRANK W. BROWN, a citizen of the United States, residing at Fort Dodge, in the county of Webster, State 5 of Iowa, have invented certain new and useful Improvements in Snowplows, of which the following is a specification.

This invention relates to plows especially adapted for removing snow.

10 Briefly stated, an important object of this invention is to provide a snow plow having novel means to scoop up the snow as it is encountered and direct it a substantial distance to one side of the road.

15 A further object of the invention is to provide a plow of the character specified having novel means whereby the discharge means of the plow may be conveniently regulated so that the point to which the snow 20 is thrown may be varied.

A further object of the invention is to provide a snow plow having a power unit for operating the snow pick-up and discharge means which is entirely separate and 25 independent from the power unit of the propelling means such as a tractor.

A still further object of the invention is to provide a snow plow which is of highly simplified construction, durable in use, and 30 cheap to manufacture.

Other objects and advantages will be apparent during the course of the following description.

In the accompanying drawings forming a 35 part of this application, and in which like numerals are employed to designate like parts throughout the same,

Figure 1 is a side elevation of the improved snow plow in use.

40 Figure 2 is a perspective of the bottom wall of a scoop embodied in the invention.

Figure 3 is a plan view of the improved snow plow, parts being shown in section,

45 Figure 4 is an end elevation of the improved plow,

Figure 5 is a perspective of one member of the housing within which one of the snow disintegrating and discharge blades operates,

50 Figure 6 is a perspective of an adjustable discharge spout embodied in the invention, and

Figure 7 is a perspective of a blade embodied in the invention.

55 Figure 8 is a vertical transverse sectional view taken on line 8—8 of Figure 1,

Figure 9 is a detail elevation of one of the casters embodied in the invention,

Figure 10 is a perspective view of a standard embodied in the invention.

In the drawings, wherein for the purpose of illustration is shown a preferred embodiment of the invention, the numeral 5 designates a frame having substantially parallel side members 6, the rear portions of which are extended inwardly as indicated at 7 and are connected to a pair of substantially parallel attaching means 8. Figure 7 illustrates that the attaching beams 8 may be arranged on opposite sides of a tractor or other propelling member 10 and connected thereto so that when the tractor is advanced, the plow will cut through the snow and operate on it in a manner to be described.

The frame 5 is also provided with a pair 75 of spaced parallel transversely extending beams 9 on which a motor 10 is mounted.

The motor is preferably of the internal combustion engine type and has connection with a transmission 12 from which a shaft 80 14 extends. The shaft 14 has connection with a chain or other suitable power transmitting member 16 which is in turn connected to a counter-shaft 16'.

The counter-shaft 16' is arranged in a 85 housing 17, the ends of which are enlarged for the reception of beveled gears 18. Fig. 3 plainly illustrates that the beveled gears 18 mesh with pinions 19 of suitable shafts 20. The stub shafts 20 are carried by anti-friction elements 21 in the enlarged end portions 22 of the housing 17 and the forward ends of the shafts 19 have connection in any suitable manner with combined snow disintegrating and fly wheels 25.

The axis of each combined balance and snow disintegrating wheel 25 is parallel to the line of travel of the machine and each wheel is provided with a plurality of radially arranged transversely curved blades 27 which directly contact with the snow. If desired, the forward edges of the blades 27 may be sharpened so as to effectively cut through the snow. Also the rear edges of the blades 27 are provided with attaching flanges 28 adapted to be secured to the members 25 by bolts, rivets, or other suitable fastening means.

Figures 3 and 4 plainly illustrate that the wheel or blades 25 are arranged side by side within separate and independent housings 30. Each housing 30 is provided with a

fixed rim or wall 31, the ends of which are arranged in spaced relation as illustrated in Figure 5. The spout 34 extends tangentially from the housing 30 and is provided with a pair of attaching extensions 35 and 36, the attaching extension 35 being secured to one end portion of the rim 31 by inwardly projecting flanges 37, while the attaching extension 36 is secured to the other end of the rim 31 by means of inwardly extending guide flanges 39. It will be seen that the spout 34 may be adjusted circumferentially on the housing 30 and it may be secured in a desired position by means of a fastening device 40 which extends through a longitudinal slot 42 in the attaching extension 36. When the fastening device 40 is tightened the discharge spout 34 is securely and positively held in a set position. It is believed to be obvious that the point at which the snow is thrown may be regulated by an adjustment of the spout 34.

Figures 2 and 3 illustrate that a scoop 50 is located in advance of the wheels 25 and is supported by suitably stout side walls 52. As the snow approaches the wheels 25 it encounters a divide 54 which directs the snow into contact with the blades of the several wheels. The end portions of the scoop 50 are also curved upwardly, as indicated at 55, so as to direct the snow into the housings which receive the several cutter wheels. It is thus seen that gradually restricted entrance openings are provided at the inlet ends of the housings and the snow is, therefore, prevented from packing about the openings.

In carrying out the invention the scoop is supported at the proper level by shoes 60 and by wheels 62 arranged rearwardly of the shoes. The shoes 60 may be provided with standards 63 connected in any suitable manner to the spaced parallel side beams 6 of the main frame.

As illustrated in Figures 1 and 8, the weight of the scoop may be taken off the shoes 60 and borne by the wheels 62. The wheels 62 are carried by standards 104 slidably through sleeves 105 carried by the frame 5. The upper portions of the standards 104 of which there are two, have connection with levers 108 through the medium of connecting heads 109 and by reference to Figure 8, it will be seen that the inner portions of the levers 108 are overlapped and have connection with a lifting chain 110. A lifting chain 112 or other suitable mechanism may be connected to the chain 110 and is suspended from a centrally located standard 114.

Figure 8 clearly illustrates that when the inner portions of the levers 108 are moved upwardly by the lifting mechanism the standards 104 will be moved downwardly whereby the weight of the scoop is borne by

the standards and the casters. This lifts the scoop to the desired position.

It is believed to be obvious that a hydraulic or other hoisting mechanism may be employed for lifting the inner portions of the levers 108.

In operation, the motor 10 is started and this results in the rotation of the wheels 25 at a speed ranging from one thousand to sixteen hundred revolutions per minute. The snow is cut by the transversely curved blades 27 and is thrown centrifugally through the spouts 34 to opposite sides of the roadway. The snow may be thrown a distance of one hundred feet or more thus clearing it off the roadway. Furthermore, as the snow is thrown with considerable force from the machine it will not fall in a row but will be spread over a rather wide area. Therefore, the snow will more rapidly melt.

A machine constructed in accordance with the present invention will effectively perform the desired work as it will cut a swath of snow three feet deep and extending for about a mile in one hour and thirty minutes.

It is to be understood that the form of the invention herein shown and described is to be taken merely as a preferred example of the same, and that such minor changes in arrangement and construction of parts may be made as will remain within the spirit of the invention and the scope of the claims.

Having thus described the invention what I claim is:

1. A snow plow comprising a plurality of housings having rims the ends of which are in spaced relationship, spouts having arcuate attaching portions overlapping the spaced ends of said rims, means adjustably connecting said attaching portions to said rims, whereby the position of said spouts may be varied, rotatable wheels arranged in the housings and having means to cut the snow and discharge it centrifugally through the spouts, and a scoop arranged in advance of the said housings and having means to direct the snow into the housings.

2. A snow plow comprising a frame having a pair of spaced parallel transversely extending beams, a motor supported by said beams and having a transmission, a shaft extending from said transmission, a transversely extending counter shaft arranged at one side of said motor and having connection with the shaft of said transmission, gears mounted on said shaft, stub shafts arranged at the ends of the counter shaft, pinions mounted on said stub shafts and engaged with said gears, wheels connected to said stub shafts and having radial transversely curved blades, a scoop for picking up the snow and applying the same to the transversely curved blades of said wheels, and a housing receiving said counter and stub shafts and said gears and being carried

- by said frame, said frame being provided with rearwardly extending attaching beams adapted to be arranged on opposite sides of a separate tractor for propelling the plow.
- 5 3. In a snow plow, the combination of a frame, a scoop carried thereby, sleeves carried by the frame, standards movable through the sleeves and having ground engaging wheels, levers connected at the outer ends thereof to the standards, a chain connected to the inner ends of the levers whereby the standards may be moved downwardly to support the weight of the scoop, and shoes carried by the frame and normally bearing the weight of the scoop.
- 10 4. In a snow plow, the combination of a frame, a scoop carried thereby, sleeves carried by the frame, standards movable through the sleeves and having ground en-
- gaging wheels, levers connected at the outer ends thereof to the standards, a chain connected to the inner ends of the levers whereby the standards may be moved downwardly to support the weight of the scoop, and shoes carried by the frame and normally bearing the weight of the scoop.
- 15 5. In a snow plow, the combination of a frame, a scoop carried thereby, means normally supporting the scoop, standards slidably carried by the frame and having ground contact members, and means connected to the standards to move the same downwardly to lift the forward portion of the scoop from the ground.

FRANK W. BROWN.
